DESIGN FOR A DISPLAY STAND

Charlotte McAleer Link, Philadelphia, Pa., assignor to E. J. McAleer and Co., Inc., Philadelphia, Pa., a corporation of Pennsylvania

Application October 29, 1947, Serial No. 142,180

Term of patent 7 years

(Cl. D80—9)

To all whom it may concern:

Be it known that I, Charlotte McAleer Link, a citizen of the United States, residing in Philadelphia, Pennsylvania, have invented a new, original, and ornamental Design for a Display Stand, of which the following is a specification, reference being had to the accompanying drawings, forming a part thereof.

In said drawings:

Fig. 1 is a front perspective view of the display stand showing my new design, and

Fig. 2 is a side elevational view of the stand.

I claim:

The ornamental design for a display stand, as shown.

CHARLOTTE McALEER LINK.
